UNITED STATES PATENT OFFICE.

GRANT GREEN, JR., OF NEW YORK, N. Y.

MACHINE FOR MANUFACTURING RAILWAY-TIES.

SPECIFICATION forming part of Letters Patent No. 591,838, dated October 19, 1897.

Application filed July 16, 1895. Serial No. 556,184. (No model.)

To all whom it may concern:

Be it known that I, GRANT GREEN, Jr., a citizen of the United States, and a resident of New York, in the county of New York and State of New York, have invented certain new and useful Improvements in Machines for Manufacturing Railway-Ties, of which the following is a specification, reference being had to the accompanying drawings, forming a part thereof, in which similar letters of reference indicate corresponding parts.

This invention relates to manufacture of railway-ties; and the object thereof is to provide a machine which will saw ties and also hew the sides thereof, it being well known that ties having hewn surfaces are much more durable and also more valuable than those having surfaces and sides formed by a saw.

The invention is fully disclosed in the following specification, of which the accompanying drawings form a part, in which—

Figure 1 is a side elevation of my improved machine; Fig. 2, an end elevation thereof; Fig. 3, a plan view of a cutter which I employ. Fig. 4 is a plan view of the entire machine. Fig. 5 is a side elevation of the machine. Fig. 6 is an end view of the machine, looking in the direction of the arrow 6. Fig. 7 is a section, on a larger scale, on line 7 of Fig. 4. Fig. 8 is a view of the cutter or hewer.

In the practice of my invention I employ an ordinary frame consisting of bottom side pieces A and cross-pieces B, the ends of a part of which are shown in dotted lines in Fig. 1.

Arranged longitudinally of the main frame and at each side thereof are side frames, the ends of which are shown in Fig. 2, and consist of vertical standards C, top cross-bars D, and longitudinal side top plates E, one of which is shown in full lines in Fig. 1, and the ends of which are shown in dotted lines in Fig. 2. Mounted between these longitudinal frames are cross-bars F, and rails G, which support a truck provided with wheels H, on which is mounted a carrier K, provided with side arms or plates L, which ex-

tend over the tops of the sides of the longitudinal frames, as shown in Fig. 2.

Connected with the under side of the carrier K is a rack-bar M, (clearly shown in Fig. 1,) which is operated by a pinion m, mounted on a shaft m', which extends transversely of the machine and is provided at its outer end with a wheel N.

The form of the reversing mechanism illustrated in Fig. 5 of the drawings, showing two pulleys for driving the carrier in opposite directions, may be actuated by any suitable means.

Mounted in each of the longitudinal frames at opposite sides are saws O, by which the ties are formed of the required size, and each of these saws is mounted on a shaft O', provided with a wheel O², and arranged beneath the shaft m' is a shaft P, which is movable, and provided with a belt-wheel P', which is adapted to be thrown into and out of contact with the wheel N by a lever p, and mounted on the shaft P is also a power-wheel p'.

As shown in the drawings, the longitudinal frame which supports the saw on the left-hand side of the machine is laterally movable or may be moved toward or from the center of the machine, the object of this arrangement being to adjust one side of the machine provided with its saw and cutter, so as to form ties of different widths and thicknesses. This result is accomplished by means of a shaft R, (shown in dotted lines in Fig. 1,) on which, at regular intervals, are mounted pinions R', which are adapted to operate in connection with rack-bars S, as shown in dotted lines in Fig. 2, which are secured transversely of the bottom of the longitudinal frame. The shaft R has mounted thereon, at one end, a ratchet-wheel or pinion T, and also a vertical lever U, to which is pivoted a crank-lever U', provided with a rod U², which extends downwardly and operates in connection with the ratchet or pinion T, as will be readily understood, and by means of the lever U the shaft R may be rotated or revolved in such manner that the pinions R' thereon will operate the rack-bars S, one of which is provided for each pinion and each of which, as herein-

- before stated, is connected with the bottom of the longitudinal frame in such manner as to move the longitudinal frame or the center portion thereof, which carries the saw and the cutter, toward or from the center of the machine. The longitudinal frame, on this side of the machine, is divided at W, forming a central portion W', and this central portion is laterally movable while the end portions will remain stationary, as will be readily understood, or if desired the entire side frame on this side of the machine may be moved toward or from the center, as hereinbefore described.
- 15 Mounted rearwardly of the saws, on each of the longitudinal frames, are cutters a, as shown in Fig. 1, which consist of central blocks b, and the cutting knives or blades d, which are rigidly secured to the opposite sides thereof and the cutting edges of which project in opposite directions, and these cutters are mounted on vertical shafts on the lower ends of which are mounted pulleys g, which are adapted to be driven or operated by power-belts, connected with the engine by which the machine is operated, in any desired manner.

Fig. 7 of the drawings represents a detail view of two cross-pieces B B in section, two rack-bars S S in section also, in place, partially inclosed within the cross-pieces B B, two pinions R' R', splined upon the shaft R, in mesh with the two rack-bars S S, and two vertical standards C C broken off near the top, which support the top plates E E. (Shown in Fig. 1 of the drawings.)

In Fig. 8 of the drawings is shown my modified form of cutter disk or head. The numeral 2 represents the case or holder for the cutters 3, the edges of which project through slots in the disk or head. The said cutters 3 are held in the cases by clamps o or screws such as are in ordinary use for similar purposes.

The numeral 1 (shown in Figs. 1, 5, and 7 of the drawings) represents the platform which supports the lower end of the standards C C, and upon the tops of which the top plates E E rest.

In operation, as will be understood, the shifting device, consisting of the shaft P, the pulley P', mounted thereon, and the lever p, connected therewith, is operated so as to bring the pulley P' into contact with the wheel N, by which the carrier is operated.

55 In Figs. 1, 2, and 4 I have shown the carriage driven from the pulley P', which is constantly rotated in one direction to drive the carriage forward by any usual or well-known means, and in Fig. 4 a modification wherein the pulley P' may be rotated in either direction by either one of the two pulleys shown, which pulleys are driven in the necessary direction by any usual or well-known means from a suitable source of power, and in both cases the pulley P' is mounted upon a carriage so as to be shifted into or out of fric-

tional contact with the pulley N by means of the lever p and its link.

The wood from which the tie is formed is placed upon the carrier A, and the saws O, 70 being revolved by the shafts O', will cut the sides thereof, or form the tie of the required width and thickness, and as the tie passes through between the cutters b, said cutters hew or cut the sides thereof, as will be readily understood, and it will be also understood that all of the sides of the tie may be similarly operated upon by passing it through the machine a second time.

Whenever it is desired to shift the position 80 of the laterally-movable frame, as hereinbefore described, so as to accommodate the machine to ties of different widths or thicknesses, the lever U is operated and the shaft R, provided with the pinions R', will operate 85 to adjust the movable portion of the frame, with which the shaft and pinions are connected, laterally or toward or from the central portion of the machine.

It will be understood that the rack-bars S 90 are connected with the bottom of the vertical standards C in the construction shown in the drawings, but these elements of construction are not material, and said rack-bars may be connected with said movable frame in any 95 desired manner, and it is apparent that many changes in the form, construction, combination, and arrangement of the various parts of my improved machine may be made without departing from the spirit of my invention or sacrificing its advantages; and I therefore reserve the right to make all such changes in the form, construction, and arrangement of the various parts as fairly come within the spirit of my invention.

In operating my machine, it is obvious and manifest, from the construction shown upon Sheet 1 of the drawings, that the carrier may be readily moved in opposite directions by revolving the transverse shaft m' and the pinion m, fixed thereon, which meshes with the longitudinal rack-bar secured to the under side of the carrier. Furthermore, it is apparent that the movable side frame may be moved to and from the central base-frame by 110 revolving the shaft R and the pinions R', fixed thereon, which mesh with the rack-bars S S, secured to the bottom of the said movable side frame.

Having fully described my invention, I 120 claim and desire to secure by Letters Patent—

1. In machines for manufacturing railway-ties, the combination of the base frame or support, the side frames, one of which is movably secured upon the base-frame, the other permanently attached thereto, the carrier longitudinally movable upon the base frame or support, and between the two side frames, the rack-bar secured to the under side of the carrier, the transverse shaft, the fixed pinion thereon, adapted to engage the said rack-bar,

- on the under side of the carrier, and means for operating, the said transverse shaft, the longitudinal shaft, the pinions thereon, and mechanism for operating said shaft and pinions, the transverse rack-bars, at the bottom of the movable side frame, whereby the said movable side frame is carried to and from the central base frame or support, substantially as herein shown and described.
- 10 2. In machines for manufacturing railway-ties, the combination of the base frame or support, the side frames, one of which is movably secured upon the base-frame, the other permanently attached thereto, the carrier longitudinally movable upon the base frame or support, and between the two side frames, the rack-bar secured to the under side of the carrier, the transverse shaft, the fixed pinion thereon, adapted to engage the said rack-bar, 15 on the under side of the carrier, and means for operating, the said transverse shaft, the saws and cutters—one saw and one cutter mounted upon the permanent side frame, and one saw and one cutter mounted upon and carried by the movable side frame, each of the said cutters or hewers in the rear of the saws, the longitudinal shaft, the pinions thereon, and mechanism for operating said shaft and pinions, the transverse rack-bars, at the bottom of the movable side frame, whereby the said movable side frame is carried to and from the central base frame or support, substantially as herein shown and described.
- 20 3. In machines for manufacturing railway-ties the combination of the said central base frame or support, the side frames of which one, is movably secured upon, and adapted to move to and from, the said central base-frame, the longitudinal, movable carrier, adapted to move longitudinally upon the central base-frame and between the side frames and provided with side arms projecting over the top of each side frame, the rack-bar attached to the under side of the said carrier, the shaft 25 extending transversely of the machine, the pinion carried by said shaft, engaging the said rack-bar the pulley on the outer end of said shaft, and means for operating the shaft, the shifting pulley, lever, and crank for operating the same, saws mounted in the side frames, and operating mechanism therefor, substantially as herein shown and described.
- 30 4. In machines for manufacturing railway-ties the combination of the central base frame or support, the two side frames, one of which is fixed to the central base-frame the other laterally movable thereon, the carrier supported upon the central base-frame, the longitudinal shaft, R, the pinions R', fixed there- 35 to, ratchet or pinion, T, upon the end of said shaft, R, the lever U, the crank-lever U', the rod U², adapted to revolve the said shaft, rack-bars S, S, secured to the bottom of the lateral, movable side frame, and means for operating said rack-bars whereby the said side frame is

moved to and from the central base-frame, substantially as herein shown and described.

5. In machines for manufacturing railway-ties, the combination of the central base frame or support, the fixed side frame, attached immovably to the said central base-frame, the laterally-movable side frame, adapted to be moved upon, and supported by the said central base-frame, the longitudinal movable carrier having laterally-projecting arms, the 75 rack-bar secured to the under side of the carrier, the shaft extending transversely of the machine, the pinion carried by said shaft, and adapted to engage the said rack-bar, the friction-pulley on the outer end of said shaft, the 80 shifting pulleys, lever and crank, for operating the carrier in opposite direction, saws, and cutters or hewers mounted in side frames, means for operating the saws and cutters, the shaft R, carrying the pinions R', fixed 85 thereon and means for revolving the said shaft, R, substantially as herein shown and described.

6. In machines for manufacturing railway-ties, the central base-frame, the side frame 90 permanently fixed thereto, the laterally-movable side frame, the longitudinal shaft R, the pinions R', splined thereon and means for revolving said shaft, the rack-bars, S, S, attached to the base of the laterally-movable 95 side frame, the carrier movable upon the central base-frame, the rack-bar, M, secured to the under side of the said carrier, the transverse shaft, m, and pinion m', fixed thereon, adapted to engage said rack-bar; M, the friction-pulley N, on the end of the transverse shaft P, shifting mechanism for moving the 100 said carrier in opposite directions, the saw and cutter or hewer mounted upon the fixed side frame, in line with each other the cutter 105 in the rear of the saw, the saw and cutter or hewer, mounted upon the laterally-movable side frame, in line with each other, the cutter in the rear of the saw, whereby two sides of the ties of different widths and thickness may 110 be sawed or slabbed and cut or hewed in passing once through the machine substantially as herein shown and described.

7. In machines for manufacturing railway-ties comprising the central base-frame, the 115 two side frames, one of which is movable laterally, the other permanently fixed to the central base-frame, the longitudinal shaft R, pinions R', splined thereto and means for revolving the said shaft, the rack-bars, S, S, secured 120 to the bottom of the laterally-movable side frame, the longitudinal movable carrier supported by said central base-frame, and adapted to be moved thereon, the rack-bar M, attached to the under side of the carrier, the 125 transverse shaft, m, the pinion fixed to the said transverse shaft, and adapted to engage the rack-bar on the under side of the said carrier, the friction-pulley on the end of the said transverse shaft, m, the shifting, sliding pul- 130

leys, lever, crank, and handle for moving the carrier in opposite directions, the saws, mounted one upon the fixed side frame, the other upon the laterally-movable side frame, the 5 cutters or hewers mounted one upon each of the fixed and laterally-movable side frames, and means for operating the saws and cutters, substantially as herein shown and described.

In testimony that I claim the foregoing as 10 my invention I have signed my name, in presence of two witnesses, this 12th day of July, 1895.

GRANT GREEN, JR.
